Specification of Letters Patent.

Patented Mar. 3, 1914.

Application filed March 18, 1912. Serial No. 684,576.

To all whom it may concern:

Be it known that we, JOHN H. GILMAN and ALBERT E. GILMAN, citizens of the United States, and residents of Ottawa, in the county of La Salle and State of Illinois, have invented certain new and useful Improvements in Elevating Apparatus, of which the following is a full, clear, and exact specification.

10 Our invention is concerned with elevating apparatus of the class used in elevating grain, etc., from wagons into bins or cribs, and is more especially concerned with elevators of the class described which are permanently located in barns, granaries, warehouses and the like; and is designed to simplify and improve such devices as have hitherto been used.

Prior to our invention, the practice has been to have a permanent elevator trough with conveyer belts or chains therein located at one side of the driveway of a barn, and a cross conveyer or drag was connected to the bottom of the elevator, which cross conveyer, in use, extended transversely of the driveway in position so that as the front end of the wagon was raised, its contents would be discharged gradually into the cross conveyer, which would carry them into the boot of the elevator, which in turn carried them up above the level of the top of the bins into which they were to be discharged. The drag or cross conveyer was pivotally connected to the bottom of the elevator trough so that it could be swung up or around to one side out of the path of the wagon as it was driven through the driveway into position to dump its contents.

By our invention, we materially simplify and improve the above described device by locating the elevator preferably directly in the path of the wagon and hinging its lower portion at a height above the top of a loaded wagon, so that when said lower portion is swung up horizontally the wagon can be driven directly beneath it into dumping position, after which said lower portion is swung down into operating position, in which position its boot is beneath the rear end of the wagon in position to receive its contents as its front end is raised. In this manner, it will be apparent that we, in our preferred construction, dispense with the drag or cross conveyer and produce a generally simpler construction.

Another feature of our invention consists in providing such a structure as we have described with suitable connections with the power shaft so that said pivoted lower end of the elevator trough can be swung up by power preparatory to dumping another load, and automatically disconnected from the power shaft when it has reached the proper height.

To illustrate our invention, we annex hereto four sheets of drawings, in which the same reference characters are used to designate identical parts in all the figures, of which,—

Figure 1 is a side elevation of our improved apparatus with a wagon associated therewith in discharging position; Fig. 1^a is a view of the upper end of the elevator, not shown in Fig. 1; Fig. 2 is a top plan view, as seen on the line A—A of Fig. 1, and with the lower portion of the elevator trough raised to its horizontal position; Fig. 3 is a side elevation of the mechanism shown in Fig. 2; Fig. 4 is an end elevation in section on the line B—B of Fig. 1; Fig. 5 is a perspective view showing the connections of the boot with the elevator trough; Fig. 6 is a perspective view on a larger scale, showing how the elevator trough is adjustably supported to take care of any sagging which may occur in the supporting floor; and Fig. 7 is a detail in side elevation of a bearing shown in perspective in Fig. 6.

Our invention is an elevator of the stationary type designed primarily for use in the driveways of barns, granaries, etc., the floor of which is indicated at 10, and 11 indicates the second floor of the building, supported upon the customary joists 12. The elevator trough consists of two sections. The upper one 13 may extend upward to any desired height and discharge into any sort of a horizontal conveying apparatus to distribute the grain into the various bins or cribs. The lower portion 14 of the trough is hinged to the upper portion in a manner which will be described more in detail subsequently. Both portions of the trough are preferably of the bucket-inclosing type and provided with the partition 16 dividing it into channels, although it will be understood that the trough may be merely a framework, as only the supporting framework for the elevating mechanism and the boot coöperating with the conveyer buckets

at the bottom are essential. The grain is carried upward in one of these channels by the conveyer buckets 17, which may be of any desired construction, which are supported by some suitable conveyer belts or chains 18 in the customary manner, these being driven from the shaft 22, which carries on its inner end the sprocket pinion 23 loosely mounted thereon, but provided with the clutch member 24 on the hub which is adapted to be engaged with the clutch member 25 rigidly secured on the shaft 22 when the bell crank lever 26 is rocked in the proper direction. A sprocket chain 27 extends from the sprocket wheel 23 to the hood 29 of the elevator trough, where it engages the sprocket wheel 30 secured on the shaft 31 suitably journaled in the sides of the hood 29. Inside of the hood at both ends of the shaft 31 are secured the large sprocket wheels 32, which are adapted to coöperate with the chains 18 previously mentioned, which chains also extend around the smaller sprocket wheels 33, suitably journaled in the boot of the elevator, for instance, by being secured on the shaft 34 journaled in said boot.

The discharge spout 35 is located to one side of the upper end of the trough 13, and the idle sprocket wheels 36 are journaled on the inner sides of the upper end of the trough 13 in suitable position to coöperate with the chains 18 to bring them back into line with the trough 13, the hood 29 of which is, as will be seen, offset so as to bring the spout 35 to one side of the trough 13. Inasmuch as the buckets 17, when moving slowly, might allow the grain to dribble out before they have reached the proper position to discharge into the spout 35, we secure between the pair of sprocket wheels 32 on the shaft 31 the preferably metallic drum 37, which serves to carry any grain thus prematurely discharged from the buckets 17 over into the vertical plane of the spout 35.

The lower portion 14 of the trough may have pivoted thereto at 38 the boot extension or hopper 39, best shown in Fig. 5, where it will be seen to consist of the base portion 40 having parallel sides 41 separated by a space slightly wider than the ends of the largest wagon beds. These sides 41 are supplemented by the converging sides 42, which serve to bring the ends of the sides adjacent the sides of the narrower trough 14, which is embraced by said sides 42. To prevent possible leakage of grain between the ends of the sides 42 and the sides of the trough 14, we secure to the inner faces of the sides of the trough 14 and the sides 42 the flexible connecting strips 43, which may be of leather, canvas, or some other suitable material. The trough 14 will, of course, be provided with the opening, shown in Fig. 5, on the hopper side, and to draw

the bottom 40 of the hopper against the bottom of the wagon bed 44, shown in Fig. 1, we preferably employ the helically coiled expanding springs 45 connected at their ends to the sides 41 of the hopper and to the outer sides of the trough 14. When the hopper is swung into position underneath the end of the wagon bed before it is raised, as indicated in dotted lines in Fig. 1, the springs 45 serve to bring the hopper up into engagement with the under side of the bed, and as the forward end of the wagon is lifted up by the dumping mechanism, and the rear end of the wagon bed is correspondingly lowered, the springs 45 will yield, as shown in full lines in Fig. 1, to accommodate the movement of the wagon, so that its contents are slowly discharged into the lower end of the elevator trough, whence they are conveyed upward by the buckets 17 and discharged through the spout 35 in the customary manner. When the lower portion 14 of the trough is to be swung up out of the way, as indicated in dotted lines in Fig. 1 and as shown in full lines in Figs. 2 and 3, the hopper 39 is held folded up against the trough 14, as shown in dotted lines in Fig. 5, by any suitable means, such as the turn-button 46 pivoted on the trough 14 and co-operating with the outer edge of the hopper 39.

As heretofore stated, the lower trough-section 14 is pivoted to the upper or main portion 13 at 15, and this pivotal joint 15 is at a sufficient height so that when the lower portion 14 is swung up into the dotted-line position shown in Fig. 1, the height of the portion 14 above the floor 10 is great enough so that the loaded wagon can be driven directly beneath the thus raised trough 14 and boot 39. When the wagon has been driven forward past the elevator to the position shown in dotted lines in Fig. 1, where it is ready to be acted upon by means of the dump mechanism 47, which may be of any desired construction and which is actuated by the shaft 19, connected to the shaft 22 by the miter gears 20 and 21, the lower portion 14 of the elevator trough can be swung down into the full-line position shown in Fig. 1, and thus operated to discharge the contents of the wagon in the manner heretofore described. To hold the lower portion 14 in its operating position, we preferably provide the stop 48 on the floor 10 and have coöoperating therewith the locking bar 49 passing through the staple 50 on the side of the trough portion 14 and pivotally secured at its upper end to the lever 51, pivoted to the side of the trough at 52. We preferably hold the lever with the bar 49 in its unlocked position by means of the helically coiled contractile spring 53 interposed between the trough 14 and the lever 51, as shown. The lever 51 may be

provided with a catch lever 54 pivoted thereon and adapted to coöperate with one or the other of a pair of apertures 55 to hold the lever in its locking or unlocking position, as may be desired. This lever 51 is preferably connected by a link 56 with the short horizontal arm of the bell crank lever 26 journaled on the bracket 57, which is suitably supported on the trough 13. This bell crank lever 26 has elongated slots 59 in the forked upper end thereof, and suitable pins or bearing blocks 60 coöperate in the customary manner with the hub of the sprocket wheel 23, so that by rocking the bell crank 26 the sprocket wheel 23 can be slid back and forth to engage or disengage its clutch member 24 with the clutch member 25 on the shaft 22.

We preferably provide means for automatically raising the lower portion 14 of the trough by the power which may be applied to the shaft 61, driven from any suitable source of power, and having thereon the sprocket wheel 62 connected by the sprocket chain 63 with the sprocket wheel 64 secured on the shaft 22. The shaft 22 has secured thereon the bevel gear 65 meshing with the bevel gear 66 secured on the end of the shaft 67, which extends horizontally beneath the upper floor 11 and the joists 12 to a point where its end serves to support the worm 68 which meshes with the worm wheel 69 secured on the end of the shaft 70 supported in suitable bearings and having the drum 71 at the other end thereof, upon which is wound the cable 72 having one end secured to said drum and the other end secured to the bottom of the lower trough portion 14, as shown in Fig. 1. The worm 68 is rigidly secured to or formed on the hub of the sprocket wheel 73 loosely mounted on the end of the shaft 67 and provided with the clutch member 74, which is adapted to coöperate with the clutch member 75 splined on the shaft 67 and having the customary annular groove 76 therein adapted to be engaged by the forked end 77 of the operating lever 78, which is preferably rigidly secured upon the horizontal rock shaft 79 parallel to the shaft 70. The shaft 79 has secured on its other end the arm 80, which is suitably located so that when the lower portion 14 of the trough reaches its horizontal position, it strikes the arm 80 and rocks it so as to move the clutch member 75 out of engagement with the clutch member 74, thus allowing the worm 68 to stop its rotation. The sprocket wheel 73 has coöoperating therewith the sprocket chain 81, which extends down to near the floor so that it can be operated manually to lower the portion 14 from the horizontal to its vertical operating position. Of course, it will be understood that we might raise the trough section 14 manually, or lower it by

the power; but we prefer the construction shown, wherein it is raised by power and lowered manually.

In some cases, where the structure of the second floor is not strong enough to prevent 70 sagging at the point where the elevator is located, we may employ the method of mounting the elevator shown in Fig. 6, where it will be seen that the pivot pins 58 are supported on the bearings 82 formed on 75 the bars 83, one end of each of which is suspended by elongated bolts 84 having their heads above the floor 11 and having their lower threaded ends extending through slightly elongated slots 85 formed in the 80 ends of the bars, so that by turning the nuts 86 the ends of the bars 83 can be raised. The other ends of these bars preferably rest on the fulcrum pieces 87 secured on the bar 88, which in turn is suspended 85 from the floor 11 by means of the elongated bolt 89 passing through the slightly elongated slot 90 in the bar 88 and provided with the nut 91 on the lower end, by which the height of the bar 88 is adjusted. With 90 this construction, it will be obvious that if any sagging of the floor 11 should occur as the building or structure settles, by turning up the nuts 86 and 91, the elevator can be raised as much as may be necessary to insure its clearing the floor 10.

While we have shown and described our invention as embodied in the form which we at present consider best adapted to carry out its purposes, it will be understood that it is 100 capable of modifications, and that we do not desire to be limited in the interpretation of the following claims except as may be necessitated by the state of the prior art.

While we have in some of the following 105 claims called the supporting members 13 and 14 a trough, it will be understood that we do not desire the said claims to be limited to a construction in which said members are true troughs, as the conveying mechanism might be supported by members which were not, properly speaking, troughs.

What we claim as new, and desire to secure by Letters Patent of the United States, is:

1. In a stationary elevator, the combination with a depending trough having a lower portion hinged to an upper portion, and a support for said upper portion, of carrying mechanism extending throughout 120 the length of the trough, and a boot terminating the lower end of said lower portion, said lower portion being adapted to be swung down to bring the boot into receiving position below the rear end of a wagon and 125 to be elevated so that the wagon can be driven directly beneath it.
2. In a stationary elevator, the combination with a depending trough having a lower portion hinged to an upper portion, 130

- 4
- and a stationary support for said upper portion, of carrying mechanism extending throughout the length of the trough, a boot terminating the lower end of said lower portion, said lower portion being adapted to be swung down to bring the boot into receiving position below the rear end of a wagon and to be elevated so that the wagon can be driven directly beneath it, of a stationary locking element outside of the conveyer, and locking means at the lower end of the lower portion coöoperating with said locking element to lock said lower portion in grain-receiving position.
- 15 3. In a stationary elevator, the combination with a depending trough having a lower portion hinged to an upper portion, and a support for said upper portion, of carrying mechanism extending throughout the length 20 of the trough, a boot terminating the lower end of said lower portion, said lower portion being adapted to be swung down to bring the boot into receiving position below the rear end of a wagon and to be elevated 25 so that the wagon can be driven directly beneath it, means for operating said carrying mechanism, and driving connections with said means which can be operated to raise the lower portion.
- 30 4. In an elevating apparatus, the combination with a depending trough having a lower portion hinged to an upper portion, and a support for said upper portion, of carrying mechanism extending throughout 35 the length of the trough, a boot terminating the lower end of said lower portion, said lower portion being adapted to be swung down to bring the boot into receiving position below the rear end of a wagon and to be 40 elevated so that the wagon can be driven directly beneath it, means for operating said carrying mechanism, driving connections with said means which can be operated to raise the lower portion, and mechanism 45 for automatically disengaging said connections when said lower end has been completely raised.
5. In an elevating apparatus, the combination with a depending trough having a lower portion hinged to an upper portion, and a support for said upper portion, of carrying mechanism extending throughout 55 the length of the trough, a boot terminating the lower end of said lower portion, a hopper discharging into the boot, and spring connections for the hopper by which it is adapted to adjust itself automatically beneath the rear end of a wagon when said lower portion is swung down to bring the 60 boot into receiving position beneath the rear end of the wagon.
6. In an elevating apparatus, the combination with a depending trough having a lower portion hinged to an upper portion, and a support for said upper portion, of carrying mechanism extending throughout the length of the trough, a boot terminating the lower end of said lower portion, a hopper discharging into the boot, and spring connections for the hopper by which it is adapted to adjust itself automatically beneath the rear end of a wagon when said lower portion is swung down to bring the boot into receiving position below the rear end of the wagon.
7. In an elevating apparatus, the combination with a depending trough having a lower portion hinged to an upper portion, of carrying mechanism extending throughout the length of the trough, a boot terminating the lower end of said lower portion, a hopper discharging into the boot, and spring connections for the hopper by which it is adapted to adjust itself automatically beneath the rear end of a wagon when said lower portion is swung down to bring the boot into receiving position below the rear end of the wagon, and flexible connections 75 between the sides of the hopper and the trough, for the purpose described.
8. In an elevating apparatus, the combination with a depending trough having a lower portion hinged to an upper portion, and a support for said upper portion, of carrying mechanism extending throughout 80 the length of the trough, a hopper pivoted to the lower end of said lower portion, said hopper being adapted to extend into receiving position beneath the rear end of a wagon when said lower portion is down, and means for holding the hopper folded against the side of the trough when the trough is up.
9. In an elevating apparatus, the combination with a depending trough having a lower portion hinged to an upper portion, and a support for said upper portion, of carrying mechanism extending throughout 85 the length of the trough, a hopper pivoted to the lower end of the lower portion of the trough, springs connecting the hopper and trough to cause the hopper to adjust itself automatically beneath the rear end of a wagon, and means for holding the hopper folded against the side of the trough when the bottom portion thereof is raised to inoperative position.
10. In an elevating apparatus, the combination with a depending trough having a lower portion hinged to an upper portion, of carrying mechanism extending throughout 90 the length of the trough, a boot terminating the lower end of said lower portion, said lower portion being adapted to be swung down to bring the boot into receiving position below the rear end of a wagon and to be elevated so that a wagon can be driven directly beneath it, a supporting structure, and bearings for the upper portion of said trough adjustably suspended from said structure.
11. In an elevating apparatus, the combination with a two-part trough, and hinges connecting the two parts, of carrying mechanism extending throughout the length of the trough, a boot terminating the lower end of said lower portion, a supporting structure, and bearings for the hinges of the trough adjustably suspended from said structure.
12. In an elevating apparatus, the combination with a two-part trough, and hinges connecting the two parts, of carrying mechanism extending throughout the length of the trough, a boot terminating the lower end of said lower portion, a supporting structure, and bearings for the hinges of the trough adjustably suspended from said structure.

- anism extending throughout the length of the trough, a boot terminating the lower end of said lower portion, a supporting structure, two parallel bars adjustably supported beneath said structure, a transverse bar supporting the adjacent ends of said parallel bars and adjustably supported from said structure, and bearings for the hinges carried by the parallel bars.
- 10 12. In an elevating apparatus, the combination with a depending trough having a lower portion hinged to an upper portion, and a support for said upper portion, of carrying mechanism extending throughout the length of the trough, a boot terminating the lower end of said lower portion, said lower portion being adapted to be swung down to bring the boot into receiving position below the rear end of a wagon and to be elevated so that the wagon can be driven directly beneath it, means for securing said lower portion with the boot in its grain-receiving position, means for operating said carrying mechanism, driving connections with said means which can be operated to raise the lower portion automatically, and mechanism for simultaneously releasing the lower portion and stopping the conveying mechanism prior to starting the driving connections to raise it.
- 15 13. In an elevating apparatus, the combination with a depending trough having a lower portion hinged to an upper portion, and a support for said upper portion, of carrying mechanism extending throughout the length of the trough, said lower portion being adapted to be swung down to bring it into receiving position beneath the rear end of a wagon and to be elevated so that the wagon can be driven directly beneath it, means for operating said carrying mechanism, driving connections for said means which can be operated to raise the lower portion, and mechanism for automatically disengaging said connections when said lower end has been raised.
- 20 14. In an elevating apparatus, the combination with a depending trough having a lower portion hinged to an upper portion, and a support for said upper portion, of carrying mechanism extending throughout the length of the trough, said lower portion being adapted to be swung down to bring it into receiving position beneath the rear end of a wagon and to be elevated so that the wagon can be driven directly beneath it, means for securing said lower portion in its grain-receiving position, means for operating said carrying mechanism, driving connections with said means which can be operated to raise the lower portion, and mechanism for simultaneously releasing the lower portion and stopping the conveying mechanism prior to starting the driving connections to raise the same.
- 25 15. In an elevating apparatus, the combination with a depending trough having a lower portion hinged to an upper portion, and a support for said upper portion, of carrying mechanism extending throughout the length of the trough, means for operating said carrying mechanism, driving connections with said means which can be operated to raise the lower portion, said driving connections consisting of a shaft driven from the operating means, a worm carried by said shaft, a worm gear, a winding drum, a transverse shaft on which said gear and drum are secured, and a cable connecting said drum and lower portion, and mechanism for automatically disengaging said connections when said lower portion has been raised, said mechanism comprising a rock shaft, an arm carried thereby in the path of the said lower portion, clutch connections between the shaft and the worm mounted thereon, and a shipper lever carried by the rock shaft and coöperating with the clutch connections.
- 30 16. In an elevating apparatus, the combination with a depending trough having a lower portion hinged to an upper portion, and a support for said upper portion, of carrying mechanism extending throughout the length of the trough, means for operating said carrying mechanism, driving connections with said means which can be operated to raise the lower portion, and mechanism coöperating with said driving connections whereby the lower portion can be lowered manually, said driving connections and mechanism comprising a shaft having a clutch member splined thereon, a worm loosely mounted on said shaft and adapted to be connected to the clutch mechanism, a worm gear, a drum connected to the worm gear, a cable connecting the drum and said lower portion, a sprocket wheel connected with the worm, a chain depending from said sprocket wheel, and a shipper lever connected with the clutch mechanism.
- 35 17. In an elevating apparatus, the combination with a depending trough having a lower portion hinged to an upper portion, and a support for said upper portion, of carrying mechanism extending throughout the length of the trough, means for operating said carrying mechanism, a shaft connected with said operating means, a clutch sleeve splined on said shaft, a worm loosely mounted on the shaft having a clutch member adapted to coöperate with the clutch sleeve, a sprocket wheel connected to said worm, a chain depending from the sprocket wheel, a worm gear meshing with the worm, a winding drum connected with the gear, a cable connecting the drum and the lower end of said lower portion, a rock shaft, an arm on said rock shaft adapted to be engaged by said lower portion when it is raised, and a

shipper lever secured on said rock shaft and engaging the clutch sleeve.

18. In an elevating apparatus, the combination with a depending trough having a lower portion hinged to an upper portion, of carrying mechanism extending throughout the length of the trough, said lower portion being adapted to be swung down to bring it into receiving position beneath the rear end of a wagon and to be elevated so the wagon can be driven directly beneath it, a supporting structure, and bearings for the upper portion of said trough adjustably suspended from said structure.
19. In a stationary elevator, the combination with a supporting member having a lower portion hinged to an upper portion, and a framework for supporting said upper portion, of elevating mechanism extending throughout the length of the member, said lower portion being adapted to be swung down to bring it into receiving position below the rear end of a wagon and to be elevated so the wagon can be driven directly beneath it, means for operating the elevating mechanism, mechanism for swinging said lower portion from its receiving position, and connections between said means and mechanism for preventing the simultaneous operation of the elevating mechanism and the swinging of the lower portion.
20. In a stationary elevator, the combination with a supporting member having a lower portion hinged to an upper portion, and a framework for supporting said upper portion, of elevating mechanism extending throughout the length of the member, said lower portion being adapted to be swung down to bring it into receiving position below the rear end of a wagon and to be elevated so the wagon can be driven directly beneath it, means for operating the elevating mechanism, means for swinging said lower portion to and from its receiving position, and connections between said operating means and swinging means for preventing their simultaneous operation.

21. In a stationary elevator, the combination with a supporting member having a lower portion hinged to an upper portion, and a framework for supporting said upper portion, of elevating mechanism extending throughout the length of the member, said lower portion being adapted to be swung down to bring it into receiving position below the rear end of a wagon and to be elevated so the wagon can be driven directly beneath it, means for operating the elevating mechanism, means for swinging said lower portion to and from its receiving position, a lock preventing the movement of said lower portion from its receiving position, and connections between said lock and the means for operating the elevating mechanism to prevent the operation of the latter while the lock is not in action.

22. In a stationary elevator, the combination with a supporting member having a lower portion hinged to an upper portion, and a framework for supporting said upper portion, of elevating mechanism extending throughout the length of the member, a boot terminating the lower end of said lower portion, said lower portion being adapted to be swung down to bring the boot into receiving position below the rear end of a wagon and to be elevated so that the wagon can be driven directly beneath it, means for operating said elevating mechanism, driving connections with said means which can be operated to raise the lower portion, and mechanism co-operating with said driving connections whereby the lower portion can be lowered manually to bring said boot into receiving position below the rear end of the wagon.

In witness whereof, we have hereunto set our hands and affixed our seals this 4th day of March A. D. 1912.
